UNITED STATES PATENT OFFICE.

JAMES E. MACWILLIAM, OF HUBBARDSTON, MASSACHUSETTS, ASSIGNOR TO FREDERICK A. MACWILLIAM, OF HUBBARDSTON, MASSACHUSETTS.

NASAL DOUCHE.

1,029,813.

Specification of Letters Patent. Patented June 18, 1912.

Application filed June 30, 1911. Serial No. 636,179.

To all whom it may concern:

Be it known that I, JAMES E. MACWILLIAM, a citizen of the United States, residing at Hubbardston, in the county of 5 Worcester and State of Massachusetts, have invented a new and useful Nasal Douche, of which the following is a specification.

The principal objects of this invention are to provide a construction of nasal douche 10 comprising a plurality of parts telescoping together in a convenient manner so as to provide a chamber for the solution, and an entirely separate and distinct chamber for storing a supply of the dry powder to be 15 used; also to provide a construction of this character in which a straining device is conveniently located without taking up any material space and one in which the parts will fit together and be removable from each 20 other in a very simple and convenient manner.

The invention also involves several improvements in other features and in details of construction as will appear hereinafter.

25 Reference is to be had to the drawings in which the figure is a central vertical sectional view of a device constructed in accordance with this invention.

The invention is shown in a form in which 30 a container A is provided for the solution. This container is provided with a flange *a* at its upper end supported from the body of the container by a bead or the like. At the top of this flange is a perforation *a'* 35 by which the device can be hung up on a nail or the like. At the bottom the container is provided with an upwardly projecting tube *a*² having a strainer at the top and preferably located centrally. This tube 40 discharges into a smaller tube *a*³ which is adapted to receive the end of a rubber tube 2 or the like which is provided with the usual nozzle when used as a nasal douche.

45 Telescoping into the portion *a* of the container is a cylinder B having a strainer *b* in the bottom and provided with a cross bar *b'* at the top for lifting the cylinder in and out. This bar preferably is of wire and is soldered or otherwise secured to the opposite sides of the cylinder. This cylinder is 50 slightly tapering, preferably being about a quarter of an inch larger in diameter at the top than at the bottom. It conveniently lets down into the portion *a* of the container A and on account of the taper of the container,

the cylinder will descend only to a certain point so that it projects up nearly to the top of the container A. Telescoping over the top of the cylinder B and container A is a receptacle C having a lower flange *c* for 60 this purpose. At the top of this flange is an imperforate bottom *c'* and above this is an external bead *c*². The portion *c*³ above the bead is for receiving a telescoping cover D. As will be seen from the drawing, the 65 part *c* of the container C projects down over the portion *a* and covers the top of the strainer B so that the bottom of the lower flange of the receptacle *c* rests on the bead *a'*. Thus the strainer B is entirely concealed. 70

The cover D rests down over the portion *c* and extends down to the bead *c*² so that the appearance of the device is attractive and it appears to be a single continuous receptacle with two beads. 75

In use the powder or other medicine to be used is carried in the container C which with its cover can be removed as a whole from the rest of the device. When it is to be used the desired quantity of medicine is 80 placed in the strainer and hot water poured through it so as to bring the solution into the bottom of the container. The container can be hung on a nail and used in the usual way. After use the parts can be put together in the position shown in the figure and the device will take up comparatively little room and can be carried around easily. 85

Although I have illustrated and described a preferred embodiment of the invention, I 90 am aware that the principles can be carried out in other ways and that the invention is not limited to all the details of construction or the particular use herein shown and described. 95

What I claim is:—

1. As an article of manufacture, a device of the character described, comprising a bottom container having an outlet at the bottom thereof and provided with an open 100 flange at the top, a strainer contained entirely within said flange, and a receptacle having an imperforate bottom and a flange projecting below said imperforate bottom adapted to cover the top flange of the container and the strainer. 105

2. As an article of manufacture, a device of the character described, comprising a lower conical container having an outlet at the bottom and provided with an open 110

flange at the top, a cylindrical strainer contained in the upper part and resting on the conical inner surface thereof, and a receptacle having an imperforate bottom and a flange extending below the bottom adapted to fit over the flange of the container so as to cover the same and the strainer.

In testimony whereof I have hereunto set my hand, in the presence of two subscribing witnesses.

JAMES E. MACWILLIAM.
